UNITED STATES PATENT OFFICE.

WILLIAM H. HOOPER, OF LYNN, MASSACHUSETTS, ASSIGNOR TO UNITED SHOE MACHINERY COMPANY, OF PATERSON, NEW JERSEY, A CORPORATION OF NEW JERSEY.

MACHINE FOR LEVELING THE SOLES OF BOOTS AND SHOES.

1,208,966.

Specification of Letters Patent. Patented Dec. 19, 1916.

Application filed March 15, 1912. Serial No. 684,016.

To all whom it may concern:

Be it known that I, WILLIAM H. HOOPER, a citizen of the United States, residing at Lynn, in the county of Essex and State of Massachusetts, have invented certain new and useful Improvements in Machines for Leveling the Soles of Boots and Shoes; and I do hereby declare the following to be a full, clear, and exact description of the invention, such as will enable others skilled in the art to which it appertains to make and use the same.

The present invention relates to machines for operating upon boot and shoe soles, and more particularly to machines of this type which comprise a shoe supporting jack and a coöperating sole leveling device relatively movable to progressively apply the pressure over different portions of the shoe sole. In certain machines of this type, and more particularly in machines of the type shown and described in the patent to Plant, No. 958,301, patented May 17, 1910, the shoe supporting jack and sole leveling device are relatively actuated to cause a progressive application of the pressure on the shoe sole and at the same time the line of support of the jack is shifted laterally to cause the leveling device to act efficiently over all portions of the shoe sole in a transverse direction. This shifting of the line of support causes the jack to oscillate in a lateral direction and unless some means are provided for controlling this oscillation, the jack tends to oscillate through an unduly great arc which tends to break the lasts and destroys the uniformity of the leveling operation.

The object of the present invention is to provide certain improvements in a machine of the character described which insure a more accurate and uniform operation upon the shoe sole and which tend to minimize the vibration of the shoe supporting jack when the machine is in operation.

With this object in view, a feature of the invention consists in the provision in a machine of the class described of means for yieldingly controlling the sidewise or lateral swinging movements of the jack when the shoe is supported in a position of pressure. Broadly considered, this feature of the invention is not limited to the employment of retarding means in connection with an

oscillatory movement of the jack due to shifting the line of support, but contemplates the use of the retarding means in connection with any machine in which a relative oscillation is imparted to the jack and leveling device due to a lateral shifting of the line of support of one of the members.

Still further features of the invention consist in certain novel features of construction, combinations and arrangements of parts hereinafter described and claimed, the advantages of which will be obvious to those skilled in the art from the following description.

In the accompanying drawings illustrating the preferred form of the invention; Figure 1 illustrates a side elevation partly in section of a shoe supporting jack and connected mechanisms embodying the features of the invention; Fig. 2 is a section on the line 2—2 of Fig. 1 illustrating the springs for controlling the sidewise movement of the jack; and Fig. 3 is a detail showing an end view of the jack carrier, and illustrating the mechanism for shifting the line of support of the jack.

The machine shown in the illustrated embodiment of the invention comprises a jack carrier 1 slidingly mounted upon the usual table and actuated by a pitman or connecting rod 2. The carrier 1 is provided with a pair of supporting arms or standards 3 which sustain the jack cradle 4 at their upper ends. The jack cradle carries the usual heel post 5 and toe post 6 upon which the shoe is mounted. The shoe is acted upon by a leveling device indicated at 7 which consists of the usual form shaped to correspond to the desired curvature of the shoe sole. The arms of the cradle are provided at their upper ends with laterally projecting heads 10, each of which rests upon a slide 11 supported to move transversely of the jack carrier and pivotally connected to a second slide 12 thus permitting the cradle to swing laterally by means of a stud 13 formed upon the slide 12. The slide 12 is supported upon a track 14 formed in the standard 3 and anti-friction means 17 are interposed between the slide 12 and track 14. The jack cradle is supported at each end by the studs 13 and the line of support of the cradle and jack is determined by the position of these

studs. In order to shift the line of support laterally, a lever 18 is pivoted to the jack carrier at 19 and engages a recess formed in the slide 12 at its upper end. This lever is actuated automatically by a cam plate, as fully described in the patent above referred to. This construction and arrangement causes a rapid vibration or oscillation of the jack cradle to take place in a lateral direction when the machine is in operation, and there is danger of this movement becoming too great if some means are not taken to limit it.

In the present invention the movement of the jack in opposite lateral directions is retarded sufficiently to prevent breakage of the lasts but a limited swinging movement of the jack is permitted to properly level the shoe. In the simplest and most efficient form of the invention which has yet been devised, this result is obtained by a pair of springs fixedly supported with relation to the jack carrier and operatively connected with the cradle to retard the movement of the cradle in opposite directions. To this end a pair of springs 20 operatively connect the jack carrier 1 with the jack cradle 4. The springs extend lengthwise of the jack and are connected to the jack carrier by upstanding studs 22 formed upon the carrier. Each spring 20 is formed of a single integral length of resilient wire coiled around one of the studs 22 and having its free end extending lengthwise of the jack carrier. The springs 20 loosely embrace the studs 22 and their rear ends are provided with upturned portions 25 which are received in slots 26 formed in a plate 27. The free ends of the springs are operatively connected with the jack cradle through a pair of downwardly projecting stop members 28 rigidly fastened to the cradle and provided with rolls 29 upon their lower ends, engaging the outside of the free ends of the springs 20. With this construction, it will be noted that the springs serve to retard the lateral or sidewise movements of the jack cradle in opposite directions, although not entirely preventing this movement. With certain styles of shoes, and more particularly those having crooked lasts, the shape of the last is such that the jack is unbalanced and is caused to assume an inclined position. With this style of last, unequal swinging movements are imparted to the jack and if some compensating mechanism is not employed, the opposite margins of the shoe are subjected to different leveling pressures. In the present invention, the jacks are caused to have equal swinging movements in opposite directions even when using a crooked last. To this end the retarding springs have provision for adjustment to unequally resist the movements of the jack in opposite directions, thus coun-

teracting the tendency of the jack to swing more in one direction than in the other. It will be obvious also that this adjustment, if desired, may be employed instead of balancing the jack and producing equal leveling pressures on opposite margins of the sole to secure a greater movement of the jack in one direction than in the other and consequently produce a greater leveling pressure upon one margin of the sole than upon the other. In the illustrated embodiment of the invention, this is accomplished by providing a transverse adjustment of the plate 27 which causes the springs 20 to be swung about the studs 22. It will be obvious that this adjustment of the plate causes the springs to assume a position oblique to the jack in which position the movements of the jack in opposite directions are retarded unequally. The adjustment of the plate 27 is readily accomplished by pivotally connecting the plate to the frame of the jack carrier at 30 and providing a tail member 31 for the plate which is connected to the frame through a bolt and slot connection indicated at 32. By loosening the holding bolt and swinging the plate 27 about the pivotal connection 30, the springs may be made to assume any desired inclination and correspondingly resist the movements of the jack cradle.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:

1. A machine for operating upon the soles of boots and shoes having, in combination, a shoe supporting jack, a leveling device, means for supporting one of the members to permit a lateral swinging movement, means for shifting the line of support of the last mentioned member transversely, and means for retarding the lateral swinging movements of the member, substantially as described.

2. A machine for operating upon the soles of boots and shoes having, in combination, a shoe supporting jack, a leveling device, means for supporting one of the members to permit a lateral swinging movement, means for shifting the line of support of the last mentioned member transversely, and means for unequally resisting the swinging movements of the member in opposite directions, substantially as described.

3. A machine for operating upon the soles of boots and shoes having, in combination, a shoe supporting jack, a leveling device, means for shifting the line of support of the jack transversely, a pair of springs con-

nected to the jack carrier, and connections between the springs and opposite sides of the jack, substantially as described.

4. A machine for operating upon the soles 5 of boots and shoes having, in combination, a shoe supporting jack, a leveling device, means for shifting the line of support of the jack transversely, a pair of springs connect- ed to the jack frame, connections between 10 the springs and opposite sides of the jack, and mechanism for adjusting the springs, substantially as described.

5. A machine for operating upon the soles of boots and shoes having, in combination, a 15 shoe supporting jack, a leveling device, means for supporting one of the members to permit a lateral swinging movement, means for shifting the line of support of the last mentioned member transversely, and a 20 spring connected to the member and ar- ranged to retard the lateral swinging move- ments of the member, substantially as de- scribed.

6. A machine for operating upon the soles 25 of boots and shoes having, in combination, a

shoe supporting jack, a leveling device, means for supporting the jack to permit a lateral swinging movement, means for shifting the line of support of the jack trans- versely, a spring connected to the jack and 30 arranged to retard the lateral swinging movements of the jack, and means for ad- justing the spring angularly, substantially as described.

7. A machine for operating upon the soles 35 of boots and shoes having, in combination, a shoe supporting jack, a leveling device, means for shifting the line of support of the jack transversely, a pair of springs ex- tending lengthwise of the jack and opera- 40 tively connected therewith at their free ends, and a plate having provision for angular adjustment and connected to the springs at their opposite ends, substantially as de- scribed.
